(57) **CLAIM**

The ornamental design for a cooking skillet, as shown and described.

DESCRIPTION

FIG. 1 is a front elevation view of a base of a cooking skillet showing the new design, shown separately from a lid of the cooking skillet to show aspects of the design that are not visible when the base and the lid are combined.

FIG. 2 is a rear elevation view thereof.

FIG. 3 is a right side elevation view thereof.

FIG. 4 is a left side elevation view thereof.

FIG. 5 is a top plan view thereof.

FIG. 6 is a bottom plan view thereof.

FIG. 7 is a front and rear elevation view of the lid of the cooking skillet, shown separately from the base to show aspects of the design that are not visible when the base and the lid are combined.

FIG. 8 is a right side elevation view thereof, the left side view being a mirror image thereof.

FIG. 9 is a top plan view thereof.

FIG. 10 is a bottom plan view thereof.

FIG. 11 is a front elevation view of the cooking skillet.

FIG. 12 is a rear elevation view thereof.

FIG. 13 is a right side elevation view thereof.

FIG. 14 is a left side elevation view thereof.

FIG. 15 is a top plan view thereof.

FIG. 16 is a bottom plan view thereof.

FIG. 17 is a top and front perspective view of the combined lid and cooking skillet; and,

FIG. 18 is a top and rear perspective view of the combined lid and cooking skillet.
